GAME BOARD

Albert Stubbmann, Flushing, N.Y., assignor to Kohner Bros., Inc., New York, N.Y., a corporation of New York

Filed Dec. 7, 1964, Ser. No. 82,934

Term of patent 14 years

(Cl. D34—5)

FIG. 1

FIG. 1 is a top plan view of a game board showing my new design;

FIG. 2 is a right side elevational view of said board; and

FIG. 3 is an enlarged fragmentary cross sectional view of said board, taken substantially along line 3—3 of FIG. 1.

The back of said board is plane.

The essential features of my design reside in the portions shown in full lines.

I claim:

The ornamental design for a game board, substantially as shown and described.
